UNITED STATES PATENT OFFICE.

CHARLES H. MCCLINTOCK, OF HARTFORD CITY, INDIANA.

COMBINED CARBURETER AND GOVERNOR FOR INTERNAL-COMBUSTION ENGINES.

No. 889,032.

Specification of Letters Patent.

Patented May 26, 1908.

Application filed August 23, 1907. Serial No. 389,775.

To all whom it may concern:

Be it known that I, CHARLES H. MCCLINTOCK, a citizen of the United States, and a resident of Hartford City, Blackford county, Indiana, have invented a new and useful Combined Carbureter and Governor for Internal-Combustion Engines, of which the following is a specification.

This invention relates to improvements in carbureters for internal combustion engines.

Objects of my invention are to provide a device of this character which will be efficient in operation, economical of manufacture, and not liable to get out of working order, and to afford means whereby the supply of air and other fuel such as the hydro-carbons of crude oil will be automatically shut completely off in case of the failure of the means by which the governor is driven.

The features of this invention consist of the novel arrangement, construction and combination of parts herein shown, whereby the feeding of the oil and air which together constitute the fuel for the operation of the engine is accomplished in an improved manner, and whereby the amount of fuel consumed by the engine will be varied proportionally to the varying degree of power developed by the engine, and whereby in case of breakage of the governor-belt, the valves of the oil-inlet and air-inlet will be automatically closed and retained in closed position.

My invention is shown arranged in operative position upon an internal-combustion engine of well known form of construction.

It will be understood that my invention may be applied to use on an engine of any suitable construction, and which is adapted to draw into its mixing chamber the admixture of air and oil or other fuel such as gasoline, by suction.

The objects of my invention, as above set forth, and other purposes which will become apparent as the specification of my invention is disclosed are accomplished by the mechanism illustrated in the preferable form of embodiment shown in the accompanying drawings, described in this specification and designated in the appended claims.

In the drawings—Figure 1 is a side view of my newly invented carbureter in operative position on an internal combustion engine of well known type, the latter being shown in section. Fig. 2 is a plan view of Fig. 1. Fig. 3 is an enlarged plan view, and Fig. 4 is an enlarged end view of my invention, the outer por-

tion of the bar 54 being broken away. Fig. 5 is a longitudinal central sectional view of Fig. 4. Fig. 6 is a transverse sectional view on line 6—6 Fig. 4.

Similar characters of reference refer to corresponding parts throughout the several views.

The smoothly bored working cylinder 1 of the engine communicates with the chamber 2; leading from this chamber is the channel 3 which terminates in the mouth 4 about which is provided a machined seat upon which my improved carbureter is suitably fastened, as plainly shown in Fig. 1. Leading from the mouth 4 into the working-cylinder are the fuel ports 5; the exhaust ports 6 communicate with the exhaust chamber through which the spent products of combustion are conveyed.

Adapted to reciprocate in the working-cylinder is the piston 8 connected by the pitman 9 to the double crank 10 of the shaft 11 upon which are retained the suitable fly wheels 12.

The frame or body of my newly devised carbureter is designed, as shown most plainly in Fig. 3 and Fig. 4, to be cast of a single piece, and is of such form and is so hollowed out that the oil-inlet member 13, the air-inlet 14 and the valve box 15 are formed. The bottom portion is flanged and machined so that the device may be effectively secured to the correspondingly machined face provided for it about the orifice for the entrance into the engine of the fuel mixture. The journal-box 16 is supported with its center in line with the center of the circular air-inlet 14, by the integrally formed arm 17, and journaled therein is the shaft 18 having the pulley 19 rigidly secured thereon at proper position, and belted to the shaft 11.

The interior end of this shaft 18 is enlarged into the sleeve 20 having integrally formed lugs in which are pivoted the centrifugal levers 21 weighted by the balls 22. Loosely retained in the bore of this sleeve is the head 23 having its end bifurcated for the reception loosely of the ends of the levers 21, the opposite end of this head 23 has a suitable bore, wherein is journaled the shaft 24, the end of the bore and the shaft being provided with the ball bearing 25 so that such friction as may occur by the impingement of the sleeve against the end of the shaft 24 is minimized. The shaft 24 is journaled at its opposite end in the threaded bushing 26 retained in the cap 27 provided with suitable

interior flange and threaded to close snugly the air-inlet 14.

28 designates a valve machined to fit nicely the bore 29 of the air-inlet, and adapted to reside loosely on the shaft 24 and to be yieldingly sustained by the coil-spring 30, against the collar 31 adjustably secured by the set screw 32 to the said shaft 24; the opposite end of the said coil-spring being adapted to bear against the interior end of the bushing 26.

Provided in the walls of the air-inlet are the ports 33, as shown in Fig. 3, and Fig. 4.

The lower edges of the valve-box are beveled and machined so as to receive the correspondingly beveled and finished edge of the valve 34 its upwardly disposed stem 35 being slidingly retained in the suitable hole provided in the top of the valve-box. Provided on this valve-stem and above the wall of the valve-box is the head 36, against the underside of which head bears the coil-spring 37, whereby the valve 34 is retained yieldingly in firm position against its seat.

25 The head 38 of the oil-inlet member is suitably bored so as to retain slidingly the plunger 39 and the upper end of this head is perforated by the small channel 40 where the pipe 41 leading from the oil supply is secured. This small channel in turn communicates with the enlarged oil passage 42 which extends about the upper end of the plunger and communicates with the oil inlet 13 whereby a free flow of the oil entering the 35 said channel is assured.

The plunger 39 is tapered on its end to fit in the cone-shaped enlargement of the passage 42; its lower end has the shoulder 43 against which the end of the coil-spring 44 having its opposite end against the head 38, is impinged. The stem 45 screwed into the end of the plunger 39 and adapted to be adjustably retained therein by the lock-nut 46, is provided with the foot 47 adapted to fit 45 movably and freely in the cam-slot 48 of the regulator head 49, as plainly shown in Fig. 5. This regulator-head is adjustably secured on the shaft 24 by the set screw 50^a, and has the cam-slot 48 provided therein to receive the 50 foot 47 above referred to. Its opposite side is formed with a straight face so that there is ample clearance between it and the top of the head 36 when the latter is in its normal uppermost position. By this formation and 55 arrangement of the parts the plunger will be retained with its foot 47 in engagement with the cam-slot 48 and the tapered end apart from the opening of the channel 40 and the width of this opening may be regulated to a 60 nicety. Also such slight tendency of the shaft 24 to revolve as there might be is thus overcome.

50 designates a sleeve adapted to fit loosely the end of the journal-box 16, the closed end 55 of this sleeve is bored to receive freely the

shaft 18. The collar 51 rigidly secured to the shaft 18 is adapted to engage the closed end of the sleeve, as plainly shown in Fig. 5. Studs 52 rigidly secured on the sides of the journal-box engage the diagonally disposed 70 slots 53 in the sleeve. These slots are so formed with reference to the studs and to each other that when a rotary motion is imparted to the sleeve it will be forced against the collar 51 and the shaft 18 will be accordingly shifted. Rigidly secured to and extending away from the sleeve 50, is the arm 54 disposed at a proper angle, upon its end which is disposed at a right angle is journaled the spool 55 adapted to ride on the belt connecting the shaft 11 of the engine and the pulley 19, as plainly shown in Fig. 1 and Fig. 3. The function of the weight 56 suitably secured on the arm 54, is to actuate the sleeve 50. When the belting 57 connecting 85 the shaft 11 of the engine, and the pulley 19, is in position the spool 55 will rest on the belting and the weight 56 will be supported.

From the foregoing disclosure of the function and construction of the various parts of my invention, it will be easily understood that in the operation of the engine the amount of oil and the amount of air desired to be fed may be regulated to answer any requirements and to the use of oils of varying density, and that as the desired speed of the engine is attained the feed of the oil and air in the proportions as fixed, will be lessened or increased, as the performance of the engine is lesser or greater, as the case may be. A much desired 100 result in devices of the character herein described is a practical means whereby the operation of the engine may be stopped in case of failure of the governor-belting. To accomplish this has been one of the main objects of 105 this invention.

While I have shown my invention embodied in a mechanism of the construction described herein and believe the best mode possible for the application of the principles of the invention has been explained, it will be understood that minor changes may be made in the parts, and forms and details which will not in the least affect the nature or principles of my invention.

When my improved combined carbureter and governor is installed in readiness for operation, it appears as shown in the drawings. As shown in Fig. 5 the plunger 39 and the valve 28, are so adjusted that the tapered head of the plunger stands apart from the cone-shaped enlargement of the passage 42, the valve 28 permits to be open the ports 33, and the valve 34 is closed. The spool 55 rests on the governor-belting as shown in 125 Fig. 1.

Simultaneously with the starting of the engine, the valve of the oil supply pipe is opened. As the carburization process progresses and the speed of the engine increases 130

the consistency of the mixture of oil and air, as the same reaches the valve 34, may be regulated to a nicety by the manipulation of the adjusting lock-nut 46 and the bushing 26.

5 After these have been set as desired so that a certain feed of fuel for a given performance may be obtained, then the quota of the combined mixture proper to be fed into the chamber, is fixed by the adjustment of the 10 regulator-head 49. The regulation of the speed of the engine is then automatically accomplished by the governor mechanism actuating the regulator-head whereby the feed of the mixed fuel is varied. In case of 15 failure for any cause of the governor-belt, then the weight 56 is unsupported, and as it drops the sleeve 50 is actuated whereby the plunger 39 and the valve 28 are instantly moved abnormally and the inlet of oil and 20 air is completely shut off, and the operation of the engine terminated.

What I claim as my invention, and desire to secure by Letters Patent, is—

1. A device of the kind described comprising 25 a mixing chamber having a puppet valve therein adapted to be retained normally closed, there being an air inlet and an oil-inlet leading into the said mixing chamber, a valve in said air-inlet and a valve in said oil-inlet, means to control the action of said valves simultaneously, a speed governor to actuate 30 said controlling means, and means to throw the governor out of operation and the valves simultaneously into closed position substantially as described.

2. A device of the kind described comprising 35 a mixing chamber having a puppet valve therein adapted to be retained normally closed, there being an air-inlet and an oil-inlet leading into the said mixing chamber, a valve in said air-inlet and a valve in said oil-inlet, independent devices to adjust the said valves, means to control the action of said valves simultaneously, a speed governor to 45 actuate said controlling means, and means to throw the governor out of operation and the valves simultaneously into closed position, substantially as described.

3. A device of the kind described comprising 50 a mixing chamber having a puppet valve therein adapted to be retained normally closed, there being an air inlet and an oil-inlet leading into the said mixing chamber, a spring-pressed valve in the oil-inlet and a spring-pressed valve in the air-inlet each having an 55

extended stem, a speed governor connected directly to the stem of the air inlet valve, a device carried by the stem of said air-inlet valve to engage the stem of the oil inlet valve whereby the latter is actuated simultaneously with the former, means to throw the governor out of operation and the valves simultaneously into closed position substantially as described.

4. A device of the kind described comprising 60 a mixing chamber having a puppet valve therein adapted to be retained normally closed there being an air-inlet and an oil-inlet leading into the said mixing-chamber, a spring-pressed valve in the oil-inlet having 65 an extended stem, a spring-pressed valve in the air-inlet the stem of which is extended into and journaled in the body portion and engaging the arms of a centrifugal governor which is journaled on a bearing supported by 70 the mixing chamber, a cam adjustably secured on said air-inlet valve stem engaging the oil-inlet valve stem, a spring to sustain the end of the air-inlet valve stem in actual engagement with the governor, and a device 75 to adjust the tension of said spring, a cam engaging said governor shaft and connected to said bearing arranged so that when moved the said valves will be simultaneously closed, substantially as described.

5. A device of the kind described comprising 80 a mixing chamber having a puppet valve therein adapted to be retained normally closed, there being an air-inlet and an oil-inlet leading into said mixing chamber, a spring-pressed valve in the oil-inlet and a 85 spring-pressed valve in the air-inlet each having an extended stem, devices to adjust the positions of said valves with reference to each other, a speed governor connected directly to the stem of the air-inlet valve, a device carried by the stem of said air-inlet valve to engage the stem of the oil-inlet valve whereby the latter is actuated simultaneously with the former, means to throw the governor 90 out of operation and the valves simultaneously into closed position substantially as described.

100 In testimony whereof I have signed my name to this specification in the presence of two subscribing witnesses.

CHARLES H. McCLINTOCK.
